UNITED STATES PATENT OFFICE.

CARL NOTBOHM, OF CATERNBERG, AND HEINRICH EIGEMANN, OF ESSEN-ON-THE-RUHR, GERMANY.

CONTROLLING DEVICE FOR HOISTING APPARATUS.

No. 899,794.

Specification of Letters Patent.

Patented Sept. 29, 1908.

Application filed April 8, 1907. Serial No. 367,059.

To all whom it may concern:

Be it known that we, CARL NOTBOHM and HEINRICH EIGEMANN, both subjects of the German Emperor, and residents of, respectively, Caternberg, Germany, and Essen-on-the-Ruhr, Germany, have invented certain new and useful Controlling Devices for Hoisting Apparatus, of which the following is a specification.

10 This invention relates to improvements in controlling devices and is especially designed for use in connection with hoisting apparatus the object of the invention being to provide a controlling device adapted to arrest operation of the hoisting engine at predetermined times, preferably when the member hoisted or lowered has reached the limit of its travel.

15 The invention will be more fully described in connection with the accompanying drawings and will be more particularly pointed out and ascertained in and by the appended claims.

20 In the drawings Figure 1 is a view in side elevation of a controlling device embodying the main features of our invention. Fig. 2 is a plan view thereof showing parts broken away and certain of the parts in section. Fig. 3 is a horizontal sectional view taken on line 3—3 of Fig. 4. Fig. 4 is a sectional view 30 on line 4—4 of Fig. 1.

Like numerals of reference designate similar parts throughout the different figures of the drawings.

25 The invention will now be described in connection with the specific form shown but it will be understood that the invention is not to be limited to such specific showing except for such limitations as the claims import.

30 The invention is illustrated in one application, *i. e.*, in connection with a hoisting apparatus, although it may be utilized in other capacities, and as shown and referring generally to the invention disclosed the same consists in the provision of a master operating

35 member in driving connection with the hoisting engine and a master element adapted to be operated by said member which element is provided with means associated with the reversing gear controller and the throttle of the 40 engine whereby upon predetermined movement of said element the means operate to retract the controller to a non-operating or neutral position and serve to close the throttle whereby further operation of the engine 45 is prevented. The invention however may

consist either in means associated with said master element for controlling the reversing gear controller or for controlling the throttle or both, the said invention in either or all of these capacities being highly efficient and serviceable. It will be further understood that the terms "throttle" and "controller" are herein used in connection with the specific application of our invention shown in connection with a hoisting apparatus merely for the purposes of a conventional illustration of one of the uses of our invention and therefore these terms are not to be understood as applying specifically to a valve for controlling the supply of pressure fluid to an engine or a lever for controlling the reversing gear of an engine.

50 As shown the structure embodying our invention comprises a base 1 provided with supporting standards 2 and 3 affording bearings for a slidably mounted controller rod 23 and similarly mounted throttle rods 41 and 42. Said standards also afford bearings for a master operating member which is specifically shown in the form of a threaded rod 4 55 rotatably and non-slidably mounted and adapted to be driven from the engine or other primary operating mechanism with which the device of our invention is adapted to be associated. As shown 63 may be considered the crank shaft of an engine and said shaft is provided with a miter gear 6 meshing with a miter 5 mounted upon the master screw 4 whereby the latter is continuously 60 driven by the engine in either direction in which the latter may be operated. The reversing gear of the engine, not herein shown 65 is associated with the controller, which as shown consists of a lever 26, by means of a connecting rod 28. The throttle valve of 70 the engine is conventionally shown at 48 and may be connected in any desired manner 75 with the engine.

Having now generally set forth the invention and the manner in which it is associated 80 with the mechanism which it is designed to control we will first specifically describe the means whereby the controller lever 26 is associated with the invention. Said lever 26 is mounted at 27 and is provided with the 85 usual quadrant 64 which latter however is not provided with notches for engagement with the usual locking device 65, the latter operating on the continuously smooth surface of the quadrant, 25 designates a con- 90

necting rod which is connected with the lever 26 and one end of a lever 24 pivoted at 66, the other end of which is connected with the controller rod 23. Said controller rod 23 is provided with controller stops which as shown consist of adjustably mounted rings 29 and 30 each provided with set bolts whereby they may be locked upon the rod 23 in any position to which they may be adjusted. The master element which as shown is in the form of a nut 7 having threaded engagement with the master screw 4 is provided with lateral extensions 8 and 9 apertured to receive guide rods 10 and 11 adapted to be fixed in the standards 2 and 3 and serving to prevent rotation of the nut 7 and permit longitudinal movement thereof upon the master screw 4. Said nut 7 is provided with transversely disposed openings or passageways, preferably two in number in which two switch members preferably in the form of bars 12 and 13 are slidably mounted, said bars being so proportioned with respect to their length as to permit shifting of the same into and out of engaging proximity with the stops 29 and 30. Said switch bars are desirably provided on their upper faces with oppositely disposed rollers 14, 15, 16 and 17 as clearly shown in Fig. 2. A controller switch 30 preferably in the form of a bar 19 is slidably mounted in a longitudinally disposed slot 18 in the nut 7 which desirably communicates with the slots in which the switch bars are formed. Said switch 19 is provided on one 35 side with cam extensions 20 and 21 and on its other side with a single cam extension 22 preferably located between the extensions 20 and 21 with reference to the length of the switch 19. Between the cams 20 and 21 and 40 opposite the ends of the cam 22 the switch 19 is provided with continuously smooth and unbroken surfaces and the cams and switch and the rollers of the switch bars are so proportioned and disposed with respect to each other that when one of the rollers, say 16, is engaged by the cam 21 the other roller 17 will engage the smooth opposite side of the bar 19. It will be obvious from the foregoing that as the switch bar 19 is shifted longitudinally lateral movement of the switch bars 12 and 13 will be effected and the cam extensions are so disposed that when one of the switch bars is shifted to an extreme position in one direction the other of said bars 45 will be shifted to an extreme position in an opposite direction the purpose of which will hereinafter more fully appear. A stationary mounting preferably in the form of a supporting tie rod 31 is mounted in the standards 2 and 3 and is provided with switch stops desirably in the form of rings 32 and 33 provided with projections 34 and 35. Said switch stops are provided with set screws 66 and 67 whereby they may be locked in any 50 desired adjusted position upon the rod 31.

By reference to Fig. 1 it will be noted that the projections 34 and 35 of said stops project into the path of said switch 19 in a manner to effect longitudinal movement thereof when the nut 7 approaches either of its extreme limits of travel.

From the foregoing it will be seen that there is provided, in connection with a master operating member and an element driven thereby and a source of power and a controller, means, preferably in the form of a switch, for automatically operating the controller 26 to retract the same to a neutral or non-operating position.

We will next describe means whereby the throttle is automatically controlled by said master operating member and element.

The throttle 48 is provided with a valve stem 68 which is connected, preferably through the medium of a manually operable lever 47, with a connecting rod 46. Said rod 46 is connected at its other end with a throttle rod shaft 44 mounted in a bearing 69 and in a bracket 45 the latter being secured to the standard 3. A lever 43 is secured near its center to the shaft 44 and at its ends is connected with the movably mounted throttle rods 41 and 42. The rod 41 is provided with a stop 50 preferably in the form of a ring having a set nut 70 whereby it may be locked in any position upon the rod 41 to which it is adjusted. Said rod 42 is provided with a stop 49 of similar construction to the stop 50 having a set nut 71.

A throttle switch desirably in the form of a bar 38 is mounted in a longitudinally disposed slot 37 formed in the nut 7 and is slideable therein. Said bar 38 is provided with oppositely disposed cam extensions 39 and 40 and said bar 38 opposite said extensions is provided with continuously smooth engaging surfaces. Immediately above said slot 37 the nut 7 is transversely slotted and there is mounted in said transverse slot a throttle switch bar 36 provided with rollers 40' and 40" adapted for engagement with said extensions 39 and 40 and with the smooth surfaces opposite the same for a purpose hereinafter to be described.

A stationary mounting preferably in the form of a supporting tie rod 53 is mounted in the standards 2 and 3 and is provided with throttle switch stops in the form of rings 54 and 55 provided with projections 56 and 57 projecting into the path of the switch 38. Said stops are as shown provided with set screws whereby they may be locked in adjusted positions.

In the present construction the parts are so adjusted that when the throttle is actuated toward a closing position it will not completely close but will admit a relatively reduced or limited amount of steam to the engine for a purpose which will hereafter more fully appear. It will however be un-

derstood that the invention is not dependent upon such adjustment of the parts, as complete cut off of the pressure fluid is not usually effected by closure of the throttle.

5 It will be obvious from the foregoing that as the switch 38 is reciprocated in opposite directions it will impart lateral movement to the switch bar 36 alternately moving the same into engaging proximity with the stops 13 49 and 50.

From the foregoing it will be seen that means, preferably in the form of a switching device, is associated with the master actuating member and master element and the 15 throttle in a manner to automatically control the same.

The operation is as follows. Assuming that the controller lever 26 occupies the 74 position, as shown in Fig. 1, which for convenience will be assumed to be that position to which the reversing gear is adjusted to drive the engine forwardly and lift the hoist bucket or cage, and that the throttle 48 is open, the master element or nut 7 will travel in the direction indicated by the arrow 58, Fig. 3. By reference to Fig. 3 it will be seen that the switch bar 36 will engage the stop 49 and reciprocate the rod 42 in a manner to partially close the throttle 48. This will result in an immediate reduction of speed of the engine but inasmuch as the throttle is not completely closed the engine will continue to run and hoist the cage. Subsequent to the closing movement of the throttle, the switch bar 38 will engage the stop 56 and the continued forward movement of the nut 7 will effect reciprocation of the bar 38 in the direction of arrow 59 thereby causing the cam 39 to shift the bar 36 from the position shown in full lines, Fig. 3, to the position shown in dotted lines so that the bar 36 will be out of engaging proximity with the stop 49. The purpose of this operation is to release the throttle and permit operation thereof by the operator by manually operating the handle 47 in case such further operation should be necessary. It is not the object of this invention to lock the throttle in a closed or closing position but merely to partially close the throttle 50 when the cage or object on the hoist rope approaches either of its extreme positions.

It will be understood that when the parts are in the position just described the engine will continue to operate, at a greatly reduced speed, and that the device of the invention will act through the controller to bring the engine to a position of rest.

As the nut 7 approaches the position just described the bar 12 will engage the stop 29, Fig. 2, and will reciprocate the rod 23 in a manner to swing the lever 26 to the neutral or 72 position. This operation will place the slide valve of the engine in a neutral position and will cut off the admission of steam to the cylinders. It will be understood however

that the cage will not at this time have reached its extreme position. It will also be understood that at this point the momentum will serve to continue to operate the parts and that the same may be arrested, if desired, by usual band-brake which however forms no feature of the present invention and is not herein shown. If breakage is not applied the momentum of the parts subsequent to the return of the lever 26 to a neutral position will be sufficient to effect engagement of the bar 19 with the stop 34 so that the cam 20 will shift the bar 12 from the position shown in full lines to the position shown in dotted lines, and the cam 22 will shift the bar 13 from the position shown in full lines to that shown in dotted lines. The bar 12 will now be out of engaging proximity with the stop 29 and the bar 13 will be in the path thereof. Now inasmuch as the cage has not reached its extreme limit of travel it is possible to obtain a slight further movement of the cage, which may under certain conditions be desirable, and the lever 26 is for this reason free to be thrown from the 72 to the 74 position. Assuming now that the engineer desires to raise the cage he will again throw the lever 26 to the 74 position and the steam passing through the partially closed throttle will operate the engine. This will result in the nut 7 traveling farther in the direction of the arrow 58 and as the bar 13 approaches the stop 29 and engages the same the lever 26 will again be thrown from the 74 to the 72 position which will indicate that the hoist bucket or cage has reached the extreme limit of travel. It is the object of this invention to at this time lock the lever 26 in the 72 or neutral position so that the engineer will be prevented from swinging the lever again toward the 74 position as it will be readily seen that such movement of the lever 26 would be prevented by engagement of the stop 29 with the bar 13. Thus it will be seen that the lever 26 is now finally thrown and locked in a neutral or 72 position and that no movement of the lever can be effected except toward the reverse or 75 position.

When the lever 26 is thrown to the 75 position the direction of operation of the parts will be reversed and the bar 13 will first engage the stop 30 to effect the first cut off of steam through the controller and subsequently the bar 12 will be thrown into engaging proximity with the stop 30, by engagement of the bar 19 with the stop 33, to effect the final cut off of steam and the locking of the lever 26 in the neutral or 72 position, this reverse operation being in all respects the same as the operation heretofore described.

In the constructions shown it will be obvious that after the throttle has been closed it will be necessary for the engineer, when re-

versing, to open the throttle by means of the lever 47.

It will be obvious that all of the objects of the invention could be realized even if the throttle controlling means were dispensed with as an effective cut off of steam could be obtained by the automatic means acting through the controller and stoppage of the cage itself at the desired point could be effected by the usual band-brake mechanism.

However it will be understood that it is preferable to partially or fully close the throttle when the cage approaches its limit of travel so as to insure a relatively reduced speed prior to complete stoppage of the cage and in view of the further fact that the engine is steadied and the cut off by the controller is made with less strain upon the parts through a partial closing of the throttle.

Having now fully described our said invention what we claim and desire to secure by Letters Patent is:

1. A controlling device for hoisting apparatus comprising in combination, a master screw driven from the hoisting engine, a master nut operated by said screw, a reversing gear controller for said engine, a movable controller rod connected with said controller and provided with adjustable stops, movable switch bars carried by said nut and adapted for engagement with said stops, a controller switch carried by said nut for throwing said bars into engagement with said stops, and stationary stops for operating said switch.

2. A controlling device for hoisting apparatus comprising in combination, a master screw driven from the hoisting engine, a master nut operated by said screw, a reversing gear controller for said engine, movable switch bars carried by said nut, a controller switch carried by said nut for operating said bars, means for operating said switch, and means whereby said switch bars operate said controller.

3. A controlling device for hoisting apparatus comprising in combination, a master operating member driven from the hoisting engine, a master element operated by said member, a controller for the reversing gear of said engine, and mechanism carried by said element for returning said controller from an operating to a non-operating position leaving said controller free, said mechanism serving subsequently to return and lock said controller in a non-operating position.

4. A controlling device for hoisting apparatus comprising in combination, a master screw, a master nut operated thereby, a throttle for the hoisting engine, oppositely movable articulated throttle rods provided with stops and connected with said throttle, a throttle switch carried by said nut, stationary stops adapted to throw said switch, and

a switch member carried by said element and operated by said switch to engage said rod stops whereby said throttle may be operated.

5. A controlling device for hoisting apparatus comprising in combination, a master operating member driven from the hoisting engine, a master element operated by said member, a controller for the reversing gear of the engine, a throttle for the engine, switch mechanism carried by said element for operating said controller, and switch mechanism carried by said element for operating said throttle.

6. A controlling device for hoisting apparatus comprising in combination, a master operating member driven from the hoisting engine, a master element operated by said member, a controller for the reversing gear of the engine, a throttle for the engine, controller switch mechanism carried by said element for operating said controller and comprising a switch and switch members, and throttle switch mechanism carried by said element for operating said throttle and comprising a switch and a switch member.

7. A controlling device for hoisting apparatus comprising in combination, a master operating member driven from the hoisting engine, a master element operated by said member, a controller for said engine, and mechanism carried by said element for returning said controller from an operating to a neutral position, said mechanism serving upon subsequent movement of said controller to its initial position to again return the same to a neutral position.

8. A controlling device for hoisting apparatus comprising in combination, a master operating member driven from the engine, a master element operated by said member, a controller for the reversing gear of the engine, a throttle for the engine, mechanism mounted on said element for operating said controller, and mechanism mounted on said element for operating said throttle.

9. A controlling device for hoisting apparatus comprising in combination, a master operating member driven from the hoisting engine, a master element operated by said member, a controller for the engine, and switch mechanism carried by said element for operating said controller and comprising a controller switch operating in the direction of travel of said element and a plurality of switch bars operated by said controller switch and movable in a direction angular to the direction of travel of said element.

10. A controlling device for hoisting apparatus comprising in combination, a master operating member driven from the hoisting engine, a master element operated by said member, a controller for the engine, and switch mechanism carried by said element for operating said controller and comprising

a controller switch and a plurality of switch bars operated thereby, said bars and switch being movable in directions angular with respect to each other.

5 11. A controlling device for hoisting apparatus comprising in combination, a master operating member driven from the hoisting engine, a master element operated by said member, a controller for the engine, and 10 switch mechanism carried by said element for operating said controller and comprising a controller switch and a plurality of switch bars.

12. A controlling device for hoisting apparatus comprising in combination, a master operating member driven from the hoisting engine, a master element operated by said member, a controller for the engine, and switch mechanism actuated by said element 20 for operating said controller and comprising a plurality of switch bars and a controller switch provided with cams for actuating said bars.

13. A controlling device for hoisting apparatus comprising in combination, a master operating member driven from the hoisting engine, a master element operated by said member, a controller for the engine, and switch mechanism carried by said element 25 30 for operating said controller and comprising

a plurality of switch bars provided with rollers and a controller switch provided with cams adapted to engage said rollers to operate said bars.

14. A controlling device for hoisting apparatus comprising in combination, a master operating member driven from the hoisting engine, a master element operated by said member, a throttle for the engine, and switch mechanism carried by said element for operating said throttle and comprising a throttle switch and a switch bar, said switch and bar operating in directions angular with respect to each other.

15. A controlling device for hoisting apparatus comprising in combination, a master operating member driven from the hoisting engine, a master element operated by said member, a throttle for the engine, and switch mechanism carried by said element for operating said throttle and comprising a throttle switch provided with cams and a switch bar provided with rollers operated by said cams.

In testimony whereof we have hereunto set our hands in presence of two witnesses.
